Application June 1, 1939, Serial No. 276,888

10 Claims. (Cl. 200—148)

This invention relates to circuit interrupters in which a high velocity blast or stream of insulating fluid is utilized to effect arc-extinction. The principal object is to improve the construction of such interrupters so that the maximum voltage and/or current interrupting capacity is increased by a more efficient utilization of the arc extinguishing blast.

According to one feature of the invention the two interrupter contacts connected to the external circuit are widely spaced to provide a relatively great arc striking distance between them; and the long arc drawn between said contacts in the open-circuit position of the interrupter is divided into a plurality of arc loops in series which are held entirely within a relatively small length of arc chute where the velocity and, consequently, the arc rupturing efficiency of the insulating fluid is relatively high. The arc chute, while relatively short, is designed to ensure efficient concentration of the stream of insulating fluid along the entire length of the arc held in said chute. By this combination of features I obtain a substantial increase in the maximum voltage interrupting capacity as compared with other known types of interrupters.

Another feature, which materially increases the maximum current interrupting capacity, resides in the provision of means for effectively dividing the total arc current into a plurality of arcs in multiple, each arc being subjected to a separate blast of air within a separate arc chute forming part of a single interrupting element.

The foregoing features of the invention are useful both separately and in combination with each other as will be made clear in the following detail description of the accompanying drawings, wherein—

Fig. 1 is a diagrammatic view of one practical embodiment of the invention.

Fig. 2 is a sectional view taken substantially along the line 2—2 of Fig. 1.

Fig. 2a is a sectional view along the line 2a—2a of Fig. 1.

Fig. 3 is a diagrammatic view of a modified embodiment of the invention.

Fig. 4 is a diagrammatic view showing certain elements of Fig. 3 on an enlarged scale.

Fig. 5 is a sectional view taken along the line 5—5 of Fig. 4.

Figs. 6 to 9 inclusive are partly diagrammatic illustrations of the embodiment appearing in Figs. 3 to 5 inclusive.

The interrupter element shown in Figs. 1 and 2 comprises widely spaced contacts 5 and 6 to which

the leads A and B of the external circuit are respectively connected. The gap between these contacts is normally bridged by a movable contact 7 which is operated to open-circuit or closed-circuit position by suitable operating means such, for example, as the operating means hereinafter described in connection with Fig. 3.

A relatively great arc striking distance is provided between contacts 5 and 6 by mounting them 10 in widely separated opposing walls 8 and 9 of the arc orifice 10, the remaining walls 11 and 12 of which are spaced apart a distance only slightly greater than the thickness of the contact 7. The width of the contact 7 along the axis 7a is equal 15 or approximately equal to the distance between the portions of the walls 8 and 9 in which the contacts 5 and 6 are mounted. It will thus be seen that the contact 7 is relatively wide and thin and is of such dimensions that only a relatively 20 small clearance is left between this contact and the arc orifice walls 11 and 12 when contact 7 is in its closed-circuit position.

In Figure 1, contact 7 is shown in its open-circuit position. The dotted lines a, b, and c indicate successive positions to which the arc drawn between contacts 5 and 7 is blown by the high velocity air or other insulating fluid which travels in the direction indicated by the arrows X. As this arc is blown beyond position c it is 25 divided, by the insulated arcing contact 13, into two sections d¹ and d² which are blown to the loop forming positions e¹ and e². Similarly, the dotted lines a¹, b¹, and c¹ indicate successive positions of the arc drawn between contacts 6 and 7. As this arc is blown beyond position c¹ it is 30 divided, by insulated arcing contact 14, into sections d³ and d⁴ which are then blown to the loop forming positions e³ and e⁴.

Contact 7 is streamlined in cross section (see 35 Fig. 2a) to provide sharp leeward edge portions 7b and 7c lying at opposite sides of a central leeward notch or recess 7d. Owing to this shaping of contact 7 the ends of the arcs which terminate on the edges 7b and 7c are effectively 40 swept along these edges until they reach the recess 7d where they are kept separated by the arcing points 7e and 7f until the arcs are extinguished by the blast after being formed into the loops e¹, e², e³, and e⁴.

Channels 18 are formed in the walls 11 and 12 45 so that the lower portions of these channels lie at opposite sides of notch 7d, as clearly shown in Fig. 1. These channels serve to direct strong blasts of air between and beyond the arcing points 7e and 7f so that the adjacent arc

sections e^2 and e^3 are prevented from coming in contact with each other.

Each of the insulated arcing contacts 13 and 14 comprises a series of relatively wide and thin contact members 15 arranged with their wide faces lying parallel with the walls 11 and 12. As clearly shown in Fig. 2, the members 15 of each series are rigidly joined together in spaced relation by a connecting web 16 which is supported from the walls 11 and 12. The upper edge of each member 15 is made concave to provide arcing points 15a and 15b separated by an intervening recess 15c. Channels 18, provided in the walls 11 and 12 at opposite sides of each of the contacts 13 and 14, serve to direct strong blasts of insulating fluid between the arcing points 15a and 15b to prevent merging of the arc sections whose adjacent ends are held by these points. The passage of insulating fluid between the thin, closely spaced members 15 of the arcing contacts 13 and 14 also serves to render non-conductive the stream of air and arc products blown from arc c and c^1 between members 15 and arcing tips 15a and 15b. The thinness and spacing of the members 15 also eliminates any possibility of the arc sections being so sheltered at the leeward edges of these members as to interfere with effective action of the extinguishing fluid.

The advantages of the construction set forth in the foregoing description will be apparent from the following observations. If the arcing contacts 13 and 14 together with the notch 1d and arcing points 1e and 1f of contact 1 were omitted the arc drawn in the open-circuit position of the interrupter would consist of only two sections, one drawn between contacts 5 and 7 and the other between contacts 6 and 7. The bight portions of the loops into which these two arc sections are formed by the elongating action of the blast fluid would be blown beyond the end 10a of the orifice and into unconfined space where the velocity of the blast is so low as to have only negligible extinguishing effect. In this case only those portions of the arc sections lying within the arc orifice are effectively acted on by the air blast. On the other hand, when each of the arcs initially drawn between contacts 5 and 7 and 6 and 7 is divided into loops in series as described herein the whole length of the arc is held within the arc orifice where the velocity and extinguishing effect of the blast of insulating fluid is at the maximum value. With the latter arrangement the arc extinguishing capacity obtainable with a given length of arc orifice and with a given quantity of air blast is much greater than would otherwise be the case.

It may also be noted at this point that with very large currents the electromagnetic repulsion between adjacent arc sections is also effective in maintaining equal spacing of the arc sections to prevent them merging together. Another feature worth noting is that the arcs drawn between the interrupter contacts are close to the walls 11 and 12 of the arc orifice 10 so that said walls assist in cooling and deionizing the arcs.

In Figs. 3, 4 and 5 I have shown a modified form of interrupter provided with means for dividing a large current into a plurality of smaller arc currents in multiple. The chief benefit realized here is a substantial increase in the maximum current interrupting capacity. Previous proposals to divide a single current into smaller arc currents in multiple have not proven feasible owing to inadequate realization of the

conditions necessary to successful execution of this idea. It is known that the quantity of arc current which can be extinguished by directing a blast of insulating fluid against a single arc is limited by the tendency of the current to concentrate into a central core-path which is of such extremely small diameter and of such extremely high density of ionization that it is not possible to effect a corresponding concentration of the air blast in exactly the same space coincident with the current path. This knowledge has prompted the development of interrupters comprising two or more sets of interrupter contacts connected in multiple but without any means being provided to ensure attainment of the desired result, namely, division of the main current into a plurality of smaller arc currents in multiple. Such interrupters have failed of their purpose owing to the fact that it is difficult to prevent the contacts of one set reaching an open-circuit position slightly in advance of the contacts of the remaining set or sets. When this occurs the current is merely shifted to the conducting paths afforded by the set or sets of interrupter contacts which are still in closed-circuit position with the result that all the current is concentrated in an arc drawn between the contacts of the set which is opened last.

Furthermore, even if it were practically possible to simultaneously open the circuit at the points of interruption provided by several sets of interrupter contacts connected in multiple, the resulting arcs could not be maintained long enough to extinguish them separately since all the arc currents would quickly be concentrated in a single arc carrying the entire current. This is due to unavoidable variations in the initial relative magnitude of multiple arc-currents. The larger arc, having the highest temperature and the least resistance, tends to take more and more of the current until the other multiple arcs are completely extinguished by this diversion of current.

The interrupter shown in Figs. 3, 4 and 5 is provided with means for dividing a single current into a plurality of smaller arc currents in multiple and for maintaining said multiple arc currents until they are disrupted by the arc-extinguishing blast of air or other insulating fluid. The manner in which this is accomplished will be clear from the following description.

The contacts 5, 6 and 7 of Figs. 3, 4 and 5 correspond to the contacts previously described in connection with Figs. 1 and 2. Additional contacts 20 and 21 are mounted in the walls 8 and 9 so that they lie directly opposite the contacts 5 and 6 and are contained in the same horizontal plane. Contact 20 is connected to contact 5 by way of conductor 22 and contact 21 is connected to contact 6 by way of resistor 23. In the closed-circuit position of the interrupter the gap between contacts 20 and 21 is bridged by a movable contact 24 which is a duplicate of the movable contact 7. The contacts 7 and 24 are fastened together by a screw 25 but are insulated from each other as indicated at 26, 27 and 28. These two contacts are offset about $\frac{1}{4}$ " so that, during opening of the circuit breaker, contact 7 passes out of engagement with contacts 5 and 6 slightly before contact 24 passes out of engagement with contacts 20 and 21. This will be clear from examination of the diagrammatic illustrations of Figs. 8 and 9.

Contacts 7 and 24 are carried by a common operating piston 30 working in cylinder 31. Piston

30 is moved into the closed circuit position shown in Fig. 5 by air admitted to the lower end of cylinder 31 through supply pipe 32. To open the interrupter a blast of air is delivered to the arc orifice or passage 10 through blast pipe 33. The force of the blast forces piston 30 downwardly so that contacts 7 and 24 are shifted to the open-circuit position shown in Figs. 4 and 5.

When the interrupter is in closed-circuit position there is a normal division of the load current between the two sets of interrupter contacts since resistor 23 is shunted by a shunt conductor 35 bridging contacts 6 and 21. This shunt conductor is held against contacts 6 and 21 by a toggle 36 when said toggle is extended as shown in Figs. 3, 4, and 6. During opening of the interrupter a blast operated trip plunger 37 is forced outwardly by the blast pressure and acts against the pivotally connected ends of the toggle levers 38 and 39 to initiate collapse of toggle 36. A spring 39a assists in separating shunt conductor 35 from contacts 6 and 21 during collapse of the toggle by plunger 37. As here shown plunger 37 is slidably mounted in a guide bore 9a so that its enlarged inner end 37a is exposed to the blast pressure in orifice 10.

In the present instance I have described a circuit breaker designed to utilize compressed air or gas as the arc extinguishing fluid. It is obvious, however, that the novel features of the invention may also be embodied in a circuit breaker adapted to utilize a suitable liquid, such as oil, as the arc extinguishing fluid. In the latter case the circuit breaker should, of course, be designed so that the oil is discharged at high velocity through the interrupting orifices and then returned to its original container.

The lower end of toggle lever 39 is provided with a laterally extending resetting arm 40 having its free end disposed above a toggle resetting piston 41 working in cylinder 42. The lower end of cylinder 42 is connected to fluid pressure supply pipe 32 by way of branch connection 43.

After each circuit interrupting operation the interrupter is reclosed by supplying pressure fluid through pipe 32 to return piston 30 and interrupter contacts 7 and 24 to closed-circuit position. A portion of the pressure fluid in pipe 32 passes through branch connection 43 and acts through piston 41 and toggle arm 40 to reset the previously collapsed toggle 36 so that shunt conductor 35 is reengaged with contacts 6 and 21.

During opening of the interrupter, arcs A and A' are initially drawn between contacts 5 and 7 and 6 and 7 since contact 7 leaves contacts 5 and 6 slightly in advance of the parting of contact 24 from contacts 20 and 21. The voltage across arcs A and A' starts current through resistor 23 (at this time shunt conductor 35 is out of engagement with contacts 6 and 21 owing to collapse of toggle 36) and the magnitude of this current increases as the arc resistance and voltage is increased by the action of the air blast so that the separation of contact 24 from contacts 20 and 21 draws arcs A² and A³ in multiple with the previously drawn arcs A and A'. In connection with the foregoing description it is assumed, for the sake of simplicity, that no change has yet taken place in the generated voltage of the external circuit and that the total current remains constant.

The arcs A and A' are blown into an arc chute L while the arcs A² and A³ are blown into a separate arc chute L', the two chutes being separated by a partition wall M so that the arcs in

each chute are subjected to a separate air blast.

In the usual case of interrupting a 60 cycle current the $\frac{1}{4}$ " difference in the relative positions of contacts 7 and 24 will be traversed in about one-eighth of a cycle and during the remainder of the half cycle arc currents will be flowing in multiple in both interrupting circuits and both arc currents will be interrupted at the first current-zero of the external circuit.

10 It is important to note in Figs. 4 and 5 that the partition M, separating arc chutes L and L', does not extend downwardly as far as the points at which the movable contacts 7 and 24 are actually separated from the cooperating stationary contacts during the opening operations of the interrupter. The termination of partition member M above such points is advantageous since it permits radiation of the intense heat and light rays from one arc (such as that comprising the arc sections A and A') to the adjacent arc space to ionize said space and thus assist in establishing the arc sections A² and A³ if the latter have not already been established by the separation of contact 24 from contacts 20 and 21.

15 20 25 The total current undergoes a reduction when current is forced to flow through the resistor by the arcing across 7, but such reduction is not the main purpose of the resistors; the main purpose being to divide the total arc current into several paths in multiple, thereby reducing the interrupting duty imposed on any one set of contacts.

30 35 The present drawings show two interrupter elements connected in multiple but it will be understood that the same principle may be embodied in circuit breakers in which two or more interrupting elements are connected in multiple.

35 40 45 Another advantage of the construction described herein is that it permits the interrupter to be closed when there is a short circuit on the system to which it is connected. The interrupter may be designed so that, during the closing operation, the contact 24 reaches closed-circuit position slightly before the contact 7, thereby dividing the total short-circuit current between the two multiple paths afforded by the two sets of interrupter contacts thus reducing burning of the contacts to a minimum. In order to further reduce burning of the contacts when closing on short circuits the interrupter may be provided with air ducts 55 and nozzles 56 through which jets of compressed air are injected between the cooperating contacts of each set. These jets of air serve to increase the dielectric strength of the space between the approaching contact points of the component contacts of each set so that these contacts are, in effect, closer together at the instant the arc strikes; and the time between striking of the arcs and the touching of the contacts which extinguishes the current-carrying arc path) is thereby reduced. The jets of air supplied through the nozzle 55 have a further beneficial effect in that they tend to sweep each arc away from the point of initial striking and thereby reduce the temperature of the metal and the amount of burning.

50 55 60 65 70 The interrupter shown in Fig. 1 comprises a single interrupting element including the stationary contacts 5 and 6 and the movable contact 7, whereas the interrupter shown in Figs. 3 and 4 comprises two interrupting elements in multiple, each element including a pair of stationary contacts and a cooperating movable contact. In view of this explanation the sense in which the term "interrupting element" is used

in the appended claims will be readily understood.

In Figure 3 I have shown an air duct 57 through which a jet of the compressed air supplied to arc orifice 10 is directed toward the contacts 6 and 21 and the cooperating shunt conductor 35. This air jet serves to increase the dielectric strength of the space which exists between the contacts 6 and 21 on the one hand and the conductor 35 on the other hand when these two sets of contacts are separated during opening of the interrupter and this permits the required motion of the fixed contacts to be minimized.

Having thus described my invention, what I claim is:

1. In a circuit breaker in which a high velocity blast or stream of insulating fluid is utilized to effect arc-extinction, the combination of means forming an arc orifice, a conduit for conveying the fluid stream to said arc orifice; said orifice, as viewed in cross section, being relatively wide along one axis constituting the major axis and relatively narrow along an intersecting axis constituting the minor axis, two opposite contacts mounted in said conduit so that their opposite surfaces are spaced apart the full width of the arc orifice measured along said major axis, a movable contact normally bridging the gap between the opposite surfaces of said first mentioned contacts, the transverse thickness of said movable contact being only slightly less than the width of the arc orifice as measured along said minor axis, said movable contact being tapered to provide sharp leeward edges inclined toward the axial center line of said orifice, the inner ends of said edges terminating at opposite sides of a central notch provided in the leeward side of said contact and channels formed in wall portions of the orifice lying at opposite sides of said notch, said channels serving to direct the arc extinguishing fluid into said notch during operation of the interrupter to open-circuit position.

2. In a circuit breaker in which a high velocity blast or stream of insulating fluid is utilized to effect arc extinction, the combination of means forming an arc orifice which, in cross section, is relatively wide along one axis constituting the major axis and relatively narrow along an intersecting axis constituting the minor axis, means for conveying the fluid stream to said orifice, two opposite contacts mounted in said arc orifice so that their opposing surfaces are spaced apart the full width of the arc orifice as measured along said major axis, a movable contact normally bridging the gap between the opposing surfaces of said first named contacts and a series of insulated arc dividing conductors located in said orifice at the leeward side of the movable contact, each of said arc dividing conductors comprising a plurality of relatively wide and thin members joined together in closely spaced relation.

3. A circuit breaker as set forth in claim 2 in which the relatively wide and thin members of each arc dividing conductor are rigidly joined together and are arranged with their wide faces lying parallel with the major axis of the arc orifice.

4. A circuit breaker as set forth in claim 2 in which the relatively wide and thin members of each arc dividing conductor are arranged with their wide faces lying parallel with the major axis of the arc orifice and are joined together in closely spaced relation by connecting webs,

each of said members being also provided with a concave upper edge affording arcing tips separated by an intervening recess.

5. In a circuit breaker in which a high velocity blast or stream of insulating fluid is utilized to effect arc extinction, the combination of means forming an arc orifice, a conduit of insulating material for conveying the fluid stream to said orifice, two contacts mounted in opposite walls of said orifice so that their opposing surfaces are spaced apart, a movable contact normally arranged to bridge the gap between the opposing surfaces of said first mentioned contacts and a pair of arc dividing conductors located in said orifice, each of said arc dividing conductors being located above and adjacent one of said first mentioned contacts and comprising a plurality of relatively wide and thin blade-like members joined together in closely spaced relation by connecting webs, each of said blade-like members being provided with a concave upper edge affording arcing tips separated by an intervening recess.

6. A circuit breaker as set forth in claim 5 in which the movable contact is provided with arcing tips extending in the direction of said arc dividing conductors.

7. In a circuit breaker in which a high velocity blast or stream of insulating fluid is utilized to effect arc extinction, the combination of means forming a plurality of arc orifices, a single conduit through which the fluid stream is conveyed to each of said orifices, two opposing contacts mounted in opposite walls of each orifice, a plurality of movable contacts, each normally bridging the gap between opposing surfaces of the contacts mounted in one of said orifices, a common operating member for operating all of said movable contacts to their circuit closing and circuit opening positions, said movable contacts being connected to said operating member in offset relation with respect to each other so that each movable contact engages and disengages its cooperating arc orifice contacts at a different time as compared with the companion movable contact or contacts, means for insulating said movable contacts from each other and an external circuit in which the several pairs of contacts mounted in the arc orifices are connected in multiple so that the total arc current in said circuit is divided into a plurality of arcs in multiple in the circuit opening position of the several movable contacts.

8. A circuit breaker as set forth in claim 7 including a resistor in series with one contact of one or more of the several pairs of contacts mounted in said arc orifice.

9. In a circuit breaker in which a high velocity blast or stream of insulating fluid is utilized to effect arc extinction, the combination of means forming a plurality of arc orifices, means for conveying the fluid stream to each of said orifices, two opposing contacts mounted in opposite walls of each orifice, a plurality of movable contacts, each normally bridging the gap between opposing surfaces of the contacts mounted in one of said orifices, a common operating member for operating all of said movable contacts to their circuit closing and circuit opening positions, said movable contacts being connected to said operating member in offset relation with respect to each other so that each movable contact engages and disengages its cooperating arc orifice contacts at a different time as compared with the companion movable contact or contacts and means for insulating said movable contacts from each other.

10. In a circuit breaker in which a high velocity blast or stream of insulating fluid is utilized to effect arc extinction, the combination of means forming a plurality of arc orifices, a single conduit through which the fluid stream is conveyed to each of said orifices, said conduit being in direct communication with all of said orifices, two opposing contacts mounted in opposite walls of each orifice, a plurality of movable contacts each normally bridging the gap between the opposing surfaces of the contacts mounted in one of said orifices, a common operating member for

5 operating all of said movable contacts to their circuit closing and circuit opening position, said operating member being arranged in said conduit and said movable contacts being connected to said operating member in offset relation with respect to each other so that each movable contact engages and disengages its cooperating arc orifice contacts at a different time as compared with the companion movable contact or contacts, and means for insulating said movable contacts from each other and from said operating member.

HUMPHREYS MILLIKEN.
